UNITED STATES PATENT OFFICE.

HENRY J. GILBERT, OF SAGINAW, MICHIGAN.

WASHBOARD.

Application filed July 21, 1924. Serial No. 727,159.

My invention relates to wash boards of small size, adapted to be held in or allowed to rest upon one hand, while the article to be washed is rubbed upon its rubbing surface 5 with the other hand, and consists, first, in the novel and improved mechanical construction of such wash board, and, second, in the provision upon the crimped rubbing surface of the board of spaces in which 10 words or letters or the like, constituting the name of the manufacturer or advertising matter, may be stamped by the same die action which forms the crimps in the rubbing surface of board.

15 In the accompanying drawing Figure 1 represents a top plan view of the wash board, showing the crimped rubbing surface and the lettering stamped in the spaces therein; Fig. 2 a bottom plan view of the 20 same, disclosing, in addition to the body of the wash board proper, a bail which may be employed, when desired, for more securely holding the wash board upon the hand; Fig. 3 a cross-section of Figure 1 on the line 25 3—3; Fig. 4 a cross-section of Figure 2 on the line 4—4.

The same letters of reference are used to indicate corresponding parts in the several views.

30 The body of the board is formed from sheet metal, preferably sheet brass, and is surrounded at its edge by an open reinforcing bead or margin A, which serves to stiffen and strengthen it. The main portion of 35 the body of the board is stamped with a suitable "crimp," as at B, to form a rubbing surface, but spaces are left in this crimped portion of the board, as at C, in which words and letters constituting the name of 40 the manufacturer, the trade name of the board, advertising matter and the like, may be stamped, as shown. The marginal bead A, the crimp B, and the lettering in the spaces C, will all be formed at one operation by means of suitable cooperating dies 45 between which the piece of sheet metal from which the board is to be formed is placed and shaped by the action of the dies.

In practical use a board so formed may

be conveniently held between the fingers and 50 thumb of the left hand, while the article to be washed is rubbed upon its rubbing surface with the right hand, but if desired the board may be provided with the bail D, Fig. 2, in which case the fingers of the left 55 hand will be slipped beneath such bail and the board held against the palm and fingers of the hand, while the article to be washed is rubbed upon its surface with the other hand.

As shown in Figure 2, the bail is provided at its ends with short lateral arms which extend at an angle to the body of the bail and have their free ends bent outward and pass through the marginal flange formed by 65 the rear wall of the bead A, to which flange they are secured. The bail is thus positioned across the back of the rubbing surface and entirely within the area thereof, the short terminal arms thereof being adjacent the inner faces of said rearward flange. This flange which extends entirely about the rear face of the board is formed by the outer wall of the bead A, which, as shown, is extended rearward from the board.

Having thus fully described my invention I claim:

1. The herein described wash board formed of a single piece of sheet metal having a crimped rubbing surface B, and a 80 surrounding marginal bead A, the outer wall of said bead forming a marginal flange about the rear face of the board, and a bail extending transversely of said rear face and having its ends secured to said flange.

2. The herein described wash board formed of a single piece of sheet metal having a crimped rubbing surface B, and a 85 surrounding marginal bead A, the outer wall of said bead forming a marginal flange about the rear face of the board, and a bail extending transversely of said rear face and provided at its ends with bent arms which extend adjacent said rearwardly projecting flange at opposite sides of the board and 90 having their ends extending through said flange.

HENRY J. GILBERT.
